AUTOMATIC PRESSURE RELIEF DEVICE FOR
CALENDERS AND THE LIKEGünther Heinz Schiffer, Krefeld, Germany, assignor to
Joh. Kleinewefers Söhne, Krefeld, Germany

Application March 22, 1956, Serial No. 573,221

Claims priority, application Germany March 25, 1955

5 Claims. (Cl. 38—52)

The present invention relates to an automatic pressure relief device for calendars and the like.

It is known to sew together piece goods to an endless piece of cloth for allowing a continuous operation of calenders and the like. In order to prevent damage to the elastic calender roll when a transverse seam passes through the calender rolls, the operator has to pay very close attention to the passing material in order to release the pressure on the respective calender roll or rolls shortly prior to the seam passing through the calender rolls. Inasmuch as this requires the continuous attention of the operator, while the safety factor is nevertheless rather low, it has been suggested to scan the seam by means of a mechanical-electrical or optical-electrical feeler or by means of compressed air operated feelers and to use the impulses conveyed by such feeler to initiate a mechanism for relieving the pressure on the respective calender roll or rolls. However, such feelers have proved insufficient inasmuch as they also respond to vibrations of the machine and furthermore to knots or spot-like dirt accumulations so that the pressure is relieved at the improper time with the result that faulty spots in the goods will be unavoidable.

It is, therefore, an object of the present invention to provide an automatic pressure relieving device for calenders and the like which will overcome the above-mentioned drawback.

It is another object of this invention to provide an automatic pressure relief device for calenders and the like which will properly relieve the pressure on the calender roll or rolls when a transverse seam is about to pass between the calender rolls while it will not react to machine vibrations and knots or spot-like dirt accumulations.

These and other objects and advantages of the invention will appear more clearly from the following specification in connection with the accompanying drawings, in which:

Fig. 1 represents a diagrammatic top view of a length of cloth containing a transverse seam, said view also showing scanning feelers arranged in conformity with the invention for scanning the seam.

Fig. 2 is a side view of the arrangement shown in Fig. 1.

Fig. 3 represents a mechanical-electrical scanning lever.

Fig. 4 illustrates an electronic control circuit for use in connection with the arrangement of Fig. 1.

General arrangement

According to the present invention two feelers are arranged in spaced relationship from each other and from the nip of the calender rolls for feeling or scanning a transverse seam in a piece of cloth passing between the feelers and one of the calender rolls. The said two feelers are offset with regard to each other in a direction transverse to the direction of movement of the cloth toward the nip of the calender rolls. When a transverse seam in the cloth is felt by the feelers, an impulse is

2

conveyed by said feelers to an electric circuit, which, however, responds only when the impulses of both feelers at the scanning points have been initiated at a time interval which corresponds to the speed of movement of said cloth over a distance corresponding to the distance between the scanning points. Therefore, all impulses which have not been produced within the said time interval will remain without any effect, thereby preventing a faulty relief of the pressure upon the respective calender roll or rolls. The time interval for causing the electric circuit to respond, i. e., to act upon the means relieving the pressure on the respective calender roll or rolls is adjustable in conformity with the required traveling speed of the respective piece of cloth. Inasmuch as the distance from the scanning point to the nip between the calender rolls is fixed, it will be appreciated that also the time interval for switching on and off the pressure relief mechanism following the scanning impulses will be dependent on the speed of rotation of the rolls, and also this time interval is variable in conformity with the desired conditions.

Structural arrangement

Referring now to the drawings in detail, the piece of cloth 1 is assumed to move in the direction of the arrow A toward and through the calender rolls 2 and 3. The roll 2 represents an elastic roll, while the roll 3 is a steel roll. At a point where the goods are supported, for instance, by the feeding roll, or, in conformity with Figs. 1 and 2, by the elastic roll 2, two feeders 5 and 6 are arranged in spaced relationship to each other and spaced from the nip between the rolls 2 and 3. As will be clearly evident from Fig. 1, the feelers 5 and 6 are offset with regard to each other in a direction transverse to the direction of movement of the cloth 1. This means that one feeler, namely feeler 5 is ahead of the other feeler, namely feeler 6 when looking in the direction of the arrow in Fig. 1, while said feelers are not in alignment with each other when looking in the direction of movement of said piece of cloth. Both feelers will thus successively respond when a seam 4 passes between said feelers and the roll 2. When these feelers respond, they close a contact which conveys an electric current impulse to an electric circuit. These impulses are evaluated automatically in this circuit and, provided the time interval between the impulses caused by the feelers 5 and 6 corresponds to the adjusted value of traveling speed of the cloth from one scanning point to another scanning point, the said electric circuit will actuate a relay 8 which in its turn brings about a relief of the pressure normally urging the roll 2 against the roll 3.

The traveling speed of the cloth is adjusted on the control device 7 by means of a pointer 7a sweeping over a dial 7b. Furthermore, the control device is so designed that the pressure relief of the respective calender roll or rolls is effected in the proper movement, i. e., shortly before the seam passes through the rolls, while the pressure relief device is made ineffective shortly after the seam has passed between the rolls. The control of the time interval between the impulses caused by the two feelers 5 and 6 can be effected in different manner, for instance by means of a delayed action relay or by a step by step switch mechanism working in a purely mechanical manner. At higher traveling speeds of the goods, however, the time interval between the two impulses is so short that arrangements of the above-mentioned type working by means of a delayed action relay or by a purely mechanical step by step switch will not any longer work satisfactorily. Therefore, in further development of the invention, there is provided an electronic control circuit according to which the charging and discharging time of a condenser by means of three thyatrons is used for ex-

amining the respective time interval. With such an arrangement, two thyatron may be employed for contact scanning, whereas by means of the third thyatron, the duration of the pressure relief of the respective calender roll or rolls up to the time the same has fully passed through the rolls can be adjusted.

The control operation in the control device 7 will then be as follows: When the first feeler 5 closes its contact 5', the negative grid voltage of the first thyatron 20 is cancelled, and the thyatron 20 fires. As a result thereof, it charges a condenser 23 which in turn causes the operating voltage of the tube 20 to drop below the firing voltage so that the tube dies again. The complete charging of the condenser 23 is secured even when the duration of a contact amounts only to three thousandths of a second. The condenser 23 now discharges itself through a variable resistance 7' which conveys the working potential of the second thyatron 21 to the feeler 6 with the contact 6'. The adjustable resistance 7' thus determines the effective time interval, i. e., the speed of movement of the cloth at which the pressure relief device will be effective. When the potential still corresponds to a charge which is in conformity with the adjusted discharge time or is greater than the latter, also the second thyatron 21 can fire when the feeler 6 closes its contact. By closing its contact 8'', the relay 8 in the anode circuit initiates the pressure relief of the respective calender roll or rolls, while closing of contact 8'' of relay 8 initiates the operation of the third thyatron 22. Movement of switch 8' into the position shown in Fig. 4 brings about the discharge of the condenser 24 through a variable resistor. The third thyatron 22 makes the device 7 ineffective and stops the same. The time of readiness of the device 7 begins anew with the last closure of the first contact of the feeler 5.

Closure of the contact 8''' actuates an electromagnet 9 the armature 39 of which displaces the piston 38 of a hydraulic control valve toward the left whereby the pressure conduit 40 of the hydraulic cylinder of the calender is connected to the discharge conduit 42. As a result thereof, the pressure fluid is discharged from the hydraulic cylinder 41 so that the lower roller 2 of the calender moves downwardly and the distance between the rollers 2 and 3 is increased. The pressure fluid is delivered by a hydraulic pump 31 and passes through conduits 32 and 36 to the hydraulic control valve. A pressure fluid storage container 35 connected to the conduit 32 will always assure that when pressure is required in the hydraulic cylinder 41, pressure will immediately be available so that the supply of pressure to the hydraulic cylinder will be effected instantly.

Fig. 3 illustrates a mechanical-electrical feeler which consists of a two arm lever 10 having one end thereof provided with a roll 10a, while the other end of the lever 10 rests against a guiding bolt 11. The lever 10 is fastened by a fish-plate 12 to a support 13, while the pressure exerted upon the roll 10a may be varied by means of a spring 15. An adjustable screw 14 acts upon and may vary the thrust of the spring 15 to thereby vary the pressure exerted upon the roll 10a. The adjustment of the spring 15 is important in order to avoid a fluttering of the lever in conformity with the conditions of the working process. The establishment of a contact is effected by means of a finally adjustable contact 17 and 5' (6'), the contact 17 being connected to the fishplate 12 by means of an insulating member 16. The fine adjustment of the contact fork can be effected in such a manner that, for instance, the feelers will not respond when butt joint seams are encountered but will safely respond when the seam interconnects overlapping portions of the cloth.

It is, of course, understood that the present invention is, by no means, limited to the particular arrangements shown in the drawings, but also comprises any modifications within the scope of the appended claims.

What I claim is:

1. In an automatic pressure relief device for use in connection with calender rolls arranged to pass textile material therebetween, which material has a seam transverse to the direction of movement of said textile material toward and between said calender rolls, the combination of: a first feeler having first contact means associated therewith and being arranged ahead of the nip of said rolls when looking in the direction of movement of said textile material, said first feeler comprising a first member for contact with said textile material, said first member being operable by a transverse seam in the material passing therebelow to close said contact means; a second feeler having second contact means associated therewith and being arranged ahead of said first feeler when looking in the direction of movement of said textile material, said second feeler comprising a second member for contact with said textile material, said second member being operable by a transverse seam in said textile material to close said second contact means; said feelers being offset with regard to each other in a direction transverse to the direction of movement of said textile material, pressure exerting means associated with at least one of said calender rolls for continuously urging said rolls relative toward each other; and means operatively connected with said members and arranged to make said pressure exerting means temporarily ineffective in response to said members being sequentially operated within a time interval corresponding to the time of travel of said material over a distance equaling the projection of the straight line distance between said members upon the longitudinal axis of the textile material passed between said calender rolls.

2. An arrangement according to claim 1, in which said members are provided with roller means for contact with said textile material.

3. In an automatic pressure relief device for use in connection with calender rolls arranged to pass textile material therebetween, which material has a seam transverse to the direction of movement of said textile material toward and between said calender rolls, the combination of: a first feeler arranged ahead of the nip of said rollers when looking in the direction of movement of said textile material, a second feeler arranged ahead of said first feeler when looking in the direction of movement of said textile material and offset with regard to said first feeler in a direction transverse to the direction of movement of said textile material, each of said feelers comprising a stationary contact member and a movable contact member and also comprising a lever carrying said movable contact member and having an element for contact with said textile material, adjustable spring means continuously urging said contact members away from each other; pressure exerting means associated with at least one of said calender rolls for continuously urging said calender rolls relative toward each other; and means operatively connected to said contact members and arranged to make said pressure exerting means temporarily ineffective in response to the two contact members of each feeler sequentially contacting each other within a time interval corresponding to the time of travel of said material over a distance equaling the projection of the straight line distance between said two feelers upon the longitudinal axis of the textile material passed between said calender rolls.

4. In an automatic pressure relief device for use in connection with calender rolls arranged to pass textile material therebetween, which material has a seam transverse to the direction of movement of said textile material toward and between said calender rolls, the combination of: a first feeler having first contact means associated therewith and being arranged ahead of the nip of said rolls when looking in the direction of movement of said textile material, said first feeler comprising a first member for contact with said textile material,

said first member being operable by a transverse seam in the material passing therebelow to close said contact means; a second feeler having second contact means associated therewith and being arranged ahead of said first feeler when looking in the direction of movement of said textile material, said second feeler comprising a second member for contact with said textile material, said second member being operable by a transverse seam in said textile material to close said second contact means; said feelers being offset with regard to each other in a direction transverse to the direction of movement of said textile material, electronic circuit means including electronic control means, each of said contact means respectively associated with said first and second feeler being arranged to be closed in response to the actuation of the respective feeler by a transverse seam in the textile material passing therebelow, and an electronic control circuit including electronic tubes and a condenser, said electronic control circuit having a first branch arranged to be closed in response to the closure of said first circuit means to thereby charge a condenser through one of said electronic tubes, said electronic circuit means also including a second branch circuit arranged to fire another one of said electronic tubes in re-

sponse to the contact means of said second feeler closing at a certain time following the closure time of said first contact means, pressure exerting means associated with at least one of said calender rolls for continuously urging said rolls relative toward each other; and means arranged to make said pressure exerting means temporarily ineffective in response to the firing of said second electronic tube at a certain time following the firing of said first electronic tube and corresponding to the time required for the travel of said seam from said first feeler to said second feeler.

5. An arrangement according to claim 4 which includes a third branch circuit with an additional electronic tube adapted to be fired simultaneously with said second electronic tube for making said means ineffective which temporarily makes said pressure exerting means ineffective to thereby restore the conditions prior to said feelers being actuated by said transverse seam.
